UNITED STATES PATENT OFFICE

163,260

LAMP

John L. Day, Grays Knob, Ky.

Application August 25, 1950, Serial No. 11,936

Term of patent 14 years

(Cl. D48—20)

To all whom it may concern:

Be it known that I, John L. Day, a citizen of the United States of America, residing at Grays Knob, in the county of Harlan and State of Kentucky, have invented a new, original, and ornamental Design for a Lamp, of which the following is a specification, reference being had to the accompanying drawings, forming part hereof.

Fig. 1 is an elevational view of a lamp, showing my new design.

Fig. 2 is a plan view thereof.

Fig. 3 is a front elevational view thereof.

Fig. 4 is a rear elevational view thereof.

Fig. 5 is a plan view of that portion of the base of the lamp under the lamp shade thereof.

I claim:

The ornamental design for a lamp, substantially as shown.

JOHN L. DAY.
